REDUCTION OF NITRO AND OTHER COMPOUNDS

Henry Dreyfus, London, England

No Drawing. Application October 17, 1932, Serial No. 638,178. In Great Britain October 22, 1931

8 Claims. (Cl. 260—69)

This invention relates to the production of organic compounds and more particularly to the production of hydrazobenzene and other reduction products of nitro compounds.

5 A number of methods for the production of hydrazobenzene are known, those employed on a commercial scale involving the reduction of nitrobenzene, azoxy- or azobenzene. Hydrazobenzene is an important intermediate product in the 10 production of benzidine into which it is converted by treatment with acid.

The reducing agent which is perhaps the most commonly employed in the production of hydrazobenzene by reduction of nitrobenzene is zinc in 15 the presence of alkali. Where zinc is employed, however, a number of unfavourable factors have to be taken into account. For example zinc is relatively expensive. Furthermore, the reaction may not only be so violent as to get out of hand, 20 but aniline may also be formed. Alcohol is usually employed to diminish the production of aniline, but its use adds considerably to the expense of the process. Where iron borings have 25 been substituted for zinc in the reduction of nitrobenzene to hydrazobenzene it has been found that other disadvantages occur. Thus a quantity of iron very considerably greater than that theoretically required to bring about complete reduction to hydrazobenzene is required in practice.

30 It has now been found that reduction is speeded up, and quantities of iron much closer to the quantities as calculated may be employed for the reduction of nitro compounds to hydrazobenzene and for other reductions, especially reductions 35 effected in neutral or alkaline media, if the iron employed as reducing agent is in a very finely divided condition, and especially if pyrophoric iron is employed.

It appears that the efficacy of the finely divided 40 iron is due to its extended surface in relation to its mass and it has been found that other forms of iron having an extended surface, for instance spongy iron produced by reduction of iron compounds, may be used successfully.

45 By using such finely divided iron or other form of iron having an extended surface in relation to its mass not only does the quantity of iron necessary for the reduction approximate much more closely to that required theoretically than is the case where iron turnings are employed, but the 50 caustic alkali such as caustic soda commonly employed in alkaline reductions may frequently without detriment be replaced wholly or in part by alkaline earth oxides or hydroxides, for example lime.

As has been indicated the iron employed should be as finely divided or have as extended a surface as possible, and may be of such a degree of subdivision as to be pyrophoric. Thus for example iron prepared by the reduction of precipitated iron hydroxide or by the reduction of iron oxide prepared by the action of heat on the nitrate is 5 eminently suitable for use in accordance with the present invention. A further convenient method for the preparation of iron suitable for the use in accordance with the present invention is by the decomposition of iron carbonyl, e. g. by the action of heat on iron carbonyl. Methods in which the iron is produced from compounds thereof at a relatively low temperature so as to 10 avoid fusion or sintering of the metal are to be preferred. The activity of the iron as a reducing agent may, if desired, be enhanced by pretreatment with caustic soda and/or with metal salt solutions, but such a pretreatment is generally unnecessary particularly where pyrophoric iron is employed.

15 As an alternative the iron carbonyl may actually be decomposed in situ the iron being thus produced in a finely divided form actually in reduction mixture.

20 The reduction of nitro compounds may be carried out at elevated temperatures, for example at 90°—100° C., and preferably is carried out in the absence of oxygen. It is preferred therefore to 25 carry out reduction in a neutral or reducing atmosphere, for example in an atmosphere of hydrogen or nitrogen.

25 If necessary or desirable the reaction may be regulated by the addition of diluents, for example 30 hydrocarbons or alcohol, to the reduction mixture, but in general such additions have not been found to be essential.

35 While the invention has been described more particularly in connection with the production 40 of hydrazobenzene by the reduction of nitrobenzene, other hydrazo compounds may be prepared by the reduction of the corresponding nitro compounds. Thus for example nitro-toluenes, nitroanisoles and nitro-xylanes may be reduced by the 45 process of the present invention. The invention furthermore is not limited to the production of hydrazo compounds, but is applicable to the production of amino, azo, or azoxy compounds by the reduction of nitro compounds, and to the reduction of nitrogen containing and other organic 50 compounds capable of reduction in general.

55 In the production of benzidine and substituted benzidines, the hydrazo compound is if necessary isolated, and then treated with acid, when con-

version to the benzidine compound takes place. Thus for example in the production of benzidine from hydrazobenzene, the hydrazobenzene may be treated with hydrochloric acid, preferably without heating, when an almost quantitative conversion is obtained. Where derivatives such as the acetyl or benzoyl derivatives of benzidine are required these may be obtained directly by heating the hydrazo compound with the organic acid or anhydride or with a mixture of the acid and anhydride. Thus for example acetyl benzidine may be obtained by boiling hydrazobenzene with acetic acid.

The following example illustrates the invention without being in any way limitative:—

Example

100 parts of nitrobenzene are stirred with 50 parts of very divided iron obtained by reducing iron oxide with hydrogen or by thermal decomposition of iron carbonyl, in a vessel containing an atmosphere of nitrogen and are then heated to about 90° C. when 80 parts of 60% caustic soda are gradually added, the temperature being maintained at about 100° C. The mixture is well stirred and when the formation of azoxybenzene is complete as shown by the setting point of the mixture, a paste of 16 parts of iron and 40 parts of 60% caustic soda is added. The mixture is stirred at the same temperature until formation of azobenzene is complete. A further 16 parts of iron and 40 parts of caustic soda are then added, the mass being maintained in a liquid state by raising the temperature towards the close of the reaction to about 130° C. When reduction is complete the crude hydrazobenzene is separated from the iron oxide and caustic alkali. To convert it into benzidine it is stirred for several hours in the cold with hydrochloric acid of 24° Bé. and the mass then heated to 80° C. the benzidine being soluble in the hot liquor. The hot solution is then filtered and the benzidine precipitated as the sulphate by the addition of sulphuric acid. The benzidine sulphate is finally filtered off, washed and the base obtained in good yield by treatment with ammonia.

What I claim and desire to secure by Letters Patent is:—

1. Process for effecting reduction of a compound selected from the group consisting of nitro compounds and reducible reduction products of nitro compounds which comprises subjecting said com-

pound to the reducing action of iron which has an extended surface in relation to its mass and which is prepared from compounds of iron by methods which avoid sintering or fusion of the metal.

2. Process for effecting reduction of a compound selected from the group consisting of nitro compounds and reducible reduction products of nitro compounds which comprises subjecting said compound to the reducing action of iron which has an extended surface in relation to its mass and which is prepared from compounds of iron by heating the same at a low temperature whereby sintering or fusion of the metal is avoided.

3. Process for effecting reduction of a compound selected from the group consisting of nitro compounds and reducible reduction products of nitro compounds which comprises subjecting said compound to the reducing action of pyrophoric iron.

4. Process for effecting reduction of aromatic nitro compounds which comprises subjecting said compounds in alkaline media to the reducing action of iron which has an extended surface in relation to its mass and which is prepared from compounds of iron by methods which avoid sintering or fusion of the metal.

5. Process for effecting reduction of aromatic nitro compounds which comprises subjecting said compounds in alkaline media to the reducing action of iron which has an extended surface in relation to its mass and which is prepared from compounds of iron by heating the same at a low temperature whereby sintering or fusion of the metal is avoided.

6. Process for the production of hydrazo benzene which comprises reducing nitrobenzene, in alkaline media with iron having an extended surface in relation to its mass and which is prepared from compounds of iron by methods which avoid sintering or fusion of the metal.

7. Process for the production of hydrazo benzene which comprises reducing nitrobenzene, in alkaline media with iron having an extended surface in relation to its mass and which is prepared from compounds of iron by heating the same at a low temperature whereby sintering or fusion of the metal is avoided.

8. Process for the production of hydrazo benzene which comprises reducing nitrobenzene, in alkaline media with pyrophoric iron.

HENRY DREYFUS.
